SPOON OR SIMILAR ARTICLE OF FLATWARE

Colin B. Richmond II, Newbury, Mass., assignor to Towle Manufacturing Company, Newburyport, Mass., a corporation of Massachusetts

Filed Feb. 24, 1965, Ser. No. 83,965

Term of patent 14 years

(Cl. D54—12)

FIG. 1 is a front elevation of a spoon or similar article of flatware showing my new design;
FIG. 2 is a side elevation;
FIG. 3 is a rear elevation; and
FIG. 4 is an enlarged transverse section taken on line 4—4 of FIG. 1.

The essential features of my design reside in the portions shown in full lines in the drawing.

I claim:

The ornamental design for a spoon or similar article of flatware, as shown and described.
